Specification of Letters Patent. Patented Mar. 20, 1917.

Application filed January 3, 1916. Serial No. 69,954.

To all whom it may concern:

Be it known that I, ARTHUR L. WOODBRIDGE, a citizen of the United States, residing at Chicago, in the county of Cook and State of Illinois, have invented new and useful Improvements in Stair Structures, of which the following is a full, clear, concise, and exact description, reference being had to the accompanying drawing, forming a part of this specification.

My invention relates to stair structure and more specifically to stair-cases of steel and concrete construction.

Among the objects of my invention is to provide such a structure which will be simple, and at the same time strong, neat in appearance and easy to erect, and in which stock parts may be used for stairways of various proportions.

Further objects will appear from the detailed description to follow taken in connection with the appended claims.

In the drawings in which I have shown one embodiment of my invention—

Figure 1 is a plan view of part of a stair-case constructed in accordance with my invention, parts being broken away;

Fig. 2 is a section on the line 2—2 of Fig. 1;

Fig. 3 is an enlarged plan view showing the connection between the tread and stringer;

Fig. 4 is a section on the line 4—4 of Fig. 3;

Fig. 5 is a perspective of part of the tread and riser member and its support; and

Fig. 6 is an enlarged vertical section showing the connection between adjacent tread and riser portions.

Referring now to the drawing in detail I have shown my invention in connection with a stair-case comprising the stringers 10, the combined tread and riser members 11, and the supporting members 12 for connecting the members 11 to the stringers 10. These supporting members 12 may be angle irons having one leg lying beneath the tread portion and supporting it, and the other leg portion extending up between the stringer

and the edge of the tread portion and secured to the stringer. Each stringer 10 may comprise a plate member 13 of sheet material and finishing and stiffening members 14 and 15 secured to the plate member 13. The members 11 may be of formed sheet metal and each comprises a tread portion 16 and

riser portion 17. The riser portion 17 may have a nose portion 18 to protect the front edge of the concrete. This nose portion may have a forwardly and upwardly extending portion 19, a vertical portion 20, and a horizontal rearwardly extending portion 21, the upper surface of which is flush with the concrete. The tread portion 16 may be provided with a forwardly and upwardly extending portion 22 engaging the portion 19. These engaging portions 22 and 19 may be pinched out at 23 and 24 to receive the bolts 25 for securing adjacent tread and riser portions together. The tread portion 16 may be cut away to form a recess 26 to accommodate the upwardly extending leg of the angle iron 12. The tread portion 16 and supporting member 12 may be punched out at 27 and 28, respectively, to receive suitable securing means such as bolts 29. The plate 13 and supporting member 12 may be punched out, as shown at 30, to receive rivets 31 to secure the members 12 to the stringers. The tread portion 16 may be covered with concrete 32.

It will be noted that in this construction the supporting members 12 may be stock parts for various sizes of tread and riser members, and that the spacing of the holes to receive the bolts 29 and rivets 31 may be the same for these different tread and riser members; also that the length of the recess 26 in the tread portion and the spacing of the holes 27 and their position relative to the recess 26 may be the same in treads of different proportions, so that the same cutters and punches will do for treads of various proportions, and so that the holes 27 and recess 26 may be made at a single operation of the press. The holes in the plate 13 for the rivets 31 may be laid out by means of a templet. The supporting members 12 may be riveted to the stringers at the shop.

In erecting the stairs the stringers are first secured in position the proper distance apart and the lower member 11 is placed in position on the supporting members 12 with the vertical leg of the angle fitting in the recess 26. It will be noted that this recess 26 serves to properly position the tread relative to the support. The bolts 29 are then put in place and tightened up. The next higher member 11 is then put in place and bolted to its support and its tread portion secured to the riser portion of the lower member 11 by means of the bolts 25. The fact that the portions 19 and 22 extend forwardly and

upwardly enables a slight adjustment to be made between these parts to take care of any slight inaccuracy in the connections between the supports 12 and the plates 13 and members 11. The vertical leg of the support 12 fitting into the recess 26 insures that the holes 27 and 28 will register with each other so that the bolts 29 can be easily inserted. Thus the whole stair structure may be erected by a single workman working from the top side of the steps. After the members 11 are all secured in position the treads may be filled in with concrete or other suitable material.

15 It will be noted that the stair-case has a very neat appearance from below as only the lower leg of the support 12 can be seen and that the construction is such that the tread is above the supporting leg of the 20 angle with its weight resting thereon and carried thereby, so that there is no tension on the bolts 29.

Having thus described my invention what I claim as new and desire to secure by Letters Patent is:—

1. A stair structure comprising a stringer, a member including tread and riser sections, and an angle iron tread support secured in substantially horizontal position to said 30 stringer and tread section, one leg of the angle iron extending beneath the tread and supporting it, and one of the sections of the member coöperating with said angle iron to determine the correct assembled position of 35 said tread section.

2. A stair structure comprising a stringer, a tread section, said tread section having a side edge recessed, and an angle iron tread support secured in substantially horizontal 40 position to said stringer and tread section, one leg of the angle iron extending beneath the tread section and supporting it and the

other leg lying in the recess and having an edge thereof engaged by a portion of the tread section to correctly position the latter. 45

3. A stair structure comprising a stringer, a member including tread and riser sections, said tread section having a side edge recessed, and an angle iron tread support secured in substantially horizontal position to said stringer and tread section, one leg of the angle iron extending beneath the tread section and supporting it and the other leg lying in the recess and having an edge thereof engaged by a portion of the member to 55 correctly position the latter.

4. A stair structure comprising a stringer, a member including tread and riser sections, said tread section having a side edge recessed, and an angle iron tread support 60 secured in substantially horizontal position to said stringer and tread section, one leg of the angle iron extending beneath the tread section and supporting it, and the other leg lying in the recess of the tread section to 65 position the tread and secure the same against movement longitudinally of the angle iron in either direction.

5. A stair structure comprising spaced stringers, a plurality of members between 70 the stringers each including tread and riser sections, the tread and riser sections of adjacent members having forwardly and upwardly-inclined portions disposed in overlying relation, securing means extending 75 through the inclined portions, and means for supporting the members from the stringers.

In witness whereof, I have hereunto subscribed my name in the presence of two witnesses.

ARTHUR L. WOODBRIDGE.
